(57) **CLAIM**

The ornamental design for a motor vehicle suspension stabilizer link, as shown and described.

DESCRIPTION

FIG. 1 is a perspective view, from above left front, of a motor vehicle suspension stabilizer link showing my new design.

FIG. 2 is a perspective view, from above right front, of a motor vehicle suspension stabilizer link showing my new design.

FIG. 3 is a front elevation view of a motor vehicle suspension stabilizer link showing my new design.

FIG. 4 is a rear elevation view of a motor vehicle suspension stabilizer link showing my new design.

FIG. 5 is a top plan view of a motor vehicle suspension stabilizer link showing my new design.

FIG. 6 is a bottom plan view of a motor vehicle suspension stabilizer link showing my new design.

FIG. 7 is a right elevation view of a motor vehicle suspension stabilizer link showing my new design.

FIG. 8 is a left elevation view of a motor vehicle suspension stabilizer link showing my new design; and,

FIG. 9 is a view taken at section 9-9 shown in FIG. 5.

1 Claim, 9 Drawing Sheets
